CLAIM

We claim the ornamental design for a tuner, as shown and described.

DESCRIPTION

FIG. 1 is a perspective view of a tuner showing my new design;

FIG. 2 is a top view thereof, with the cover completely removed;

FIG. 3 is a top view thereof, with a solid cover attached;

FIG. 4 is a top view thereof, with a translucent cover attached;

FIG. 5 is a bottom plan view thereof;

FIG. 6 is a front plan view thereof;

FIG. 7 is a back plan view thereof;

FIG. 8 is a left side elevation view thereof; and,

FIG. 9 is a right side elevation view thereof.

The broken lines in the drawings showing the arcs, circles, ovals, rectangles and features, words and symbols on the top and bottom faces are for illustrative purposes only and form no part of the claimed design.
